(57) **CLAIM**

The ornamental design for an LED lamp, as shown and described.

DESCRIPTION

FIG. 1 is a front view of the LED lamp of the present invention.

FIG. 2 is a back view of the LED lamp.

FIG. 3 is a side view of the LED lamp.

FIG. 4 is a side view of the LED lamp, showing the opposite side from FIG. 3.

FIG. 5 is a bottom view of the LED lamp.

FIG. 6 is a top view of the LED lamp.

FIG. 7 is a perspective view of the LED lamp, viewed from an angle above the lamp; and,

FIG. 8 is a perspective view of the LED lamp, viewed from an angle below the lamp.
